UNITED STATES PATENT OFFICE

JOSEPH LEDWINKA, OF PHILADELPHIA, PENNSYLVANIA, ASSIGNOR TO BUDD MANUFACTURING COMPANY, OF PHILADELPHIA, PENNSYLVANIA, A CORPORATION OF PENNSYLVANIA

VEHICLE CURTAIN ROD SOCKET

Application filed March 12, 1926. Serial No. 94,224.

This invention relates to vehicle bodies, and more particularly to means for supporting side curtains for enclosing the interior of such bodies.

5 It has heretofore been proposed to arrange the curtain holding means in such a manner that the curtains are supported by the door, and so that the curtain opens with the door.

10 The general object of the present invention is to provide an improved curtain rod socket or holder, so constructed that it can be mounted inside of a vehicle door between the inner and outer panels thereof. Subsidiary objects are to provide a rod socket of this nature which shall be strong in construction, cheap to manufacture, and which will hold the rod against rotation.

With the above and other objects in view, 20 the invention consists in the construction and arrangement of parts hereinafter described and claimed and illustrated in the accompanying drawings, in which:—

25 Figure 1 is a conventional view of the side of a vehicle body showing a curtain rod carried by the door thereof;

Figure 2 is an enlarged side elevation of my improved socket complete, the view being taken looking from the outside of the 30 vehicle, and the outer panel of the door being broken away for the sake of clearness;

Figure 3 is a central vertical section therethrough, substantially on the line 3—3 of Figure 2;

35 Figure 4 is a side elevation of the improved socket member which I have devised;

Figure 5 is an end view thereof taken as indicated by the line 5—5 of Figure 4; and

40 Figure 6 is a sectional view on a reduced scale, substantially on the line 6—6 of Figure 3, looking in the direction of the arrow.

Referring to the drawings in detail, A designates a vehicle body and B one of the side doors thereof. At C is shown a curtain supported by a curtain rod D, carried by the door. My improved socket is for the purpose of holding the lower end of this curtain rod D.

45 Referring to Figures 2 and 3, the device 50 comprises a bracket 1, preferably compris-

ing a flat plate of somewhat triangular configuration, as shown, which plate is adapted to be rigidly attached to the inner panel 5 of the door as by means of rivets 4. This plate is provided at its lower and upper 55 edges with spaced parallel ears 2 and 3, preferably turned up from the same sheet metal blank as the plate. These ears have openings therethrough, the opening in the upper ear 3 being somewhat larger than the diameter of the curtain rod and the opening in the lower ear being more restricted, for a purpose hereinafter described.

60 6 designates the outer panel of the door and 7 the upper or top edge thereof. This 65 upper edge is provided with an opening 7^a of a size to receive the curtain rod D and so located as to register with the opening in the upper ear 3.

65 Referring to Figure 6, it will be seen that 70 the door B is provided with a rabbeted edge, as usual, such edge having an inner portion 8 and a shoulder 9 extending from the portion 8 substantially parallel with the plane 75 of the door.

70 My improved bracket comprises, in addition to the ears 2 and 3, a flange portion 10 lying at right angles to the plate 1, and adapted to rest against the inner portion 8 of the edge of the door. The free edge of 80 the flange 10 carries a tongue or lip 11, which is adapted to be bent over and welded or otherwise secured to the shoulder 9 of the door, as clearly shown in the drawings. Thus, my improved bracket is rigidly secured to the door at both sides of the ears 85 2 and 3.

85 In addition to the bracket above described, I provide a socket member 12 illustrated in Figures 4 and 5. This is preferably pressed from a sheet metal blank and comprises a cylindrical body 12 having a crack or open joint 13 extending longitudinally thereof and provided at its upper end with an outward turned radial flange 14. The open joint 13 90 permits the socket member 12 to resiliently engage the bracket when it is installed and thereby prevent rattling.

95 It is desirable that the curtain rod should be held against rotation in the socket and 100

to accomplish this, I draw in or compress the lower end of the socket member 12 to form a restricted opening 15, which opening as clearly shown in Figure 5, is polygonal. By this term, I of course wish to be understood 5 as meaning any shape other than round.

At its extreme lower end, the socket member carries a pair of lugs 16, which are originally parallel, as shown in full lines in Figure 4, but which are adapted to be bent 10 over into the position indicated in dotted lines.

It will now be understood that the socket member shown in Figures 4 and 5 is mounted in and extends between the ears 2 and 3 15 of my improved bracket, as clearly shown in Figure 3, the ends of the socket member being received within the openings in the ears 2 and 3, and the flange 14 resting upon the top of ear 3. The lugs 16 pass through the opening in the ear 2 and are then bent 20 over laterally to engage the under side of this ear, as shown in Figure 3, to securely lock the parts in assembled relation.

25 In order to hold the rod D against rotation, I reduce or form the extreme lower end thereof so as to fit within the polygonal opening 15 at the bottom of the socket, as indicated at E in Figure 3. It will be obvious that by reason of this reduced end or 30 tang entering the socket 15, the rod will be prevented from rotating, but can be freely withdrawn from the socket at any time.

Also as shown in Figure 3, it will be noted 35 that the axis of the rod and socket are disposed at an angle to the plane of the door. This is necessary in many cases where the width of the body at the door level is less than the width of the top. In other words, 40 the top overhangs the body, and for this reason, the curtain rods assume an inclined position.

What I claim is:—

1. A curtain rod socket comprising a sheet 45 metal supporting fixture having a relatively unyielding seat of fixed dimension, and a socket proper slit throughout its main body and supported in said seat under radial tension, whereby the resiliency of the socket is 50 made use of to prevent lost motion in said fixture.

2. A curtain rod socket structure comprising 55 a support providing spaced integral ears, a circular opening in the upper ear, a polygonal opening of similar dimensions in the lower ear, a curtain rod having a socket proper comprising a cylindrical barrel substantially of the diameter of the upper opening having an outward integral lip flange 60 and a polygonal extremity engaged within the lower opening of the lower ear.

3. A curtain rod socket circular throughout 65 its main body and polygonal at its lower extremity only for reception in a correspondingly-shaped seat for preventing rota-

tion of the socket, and integral retaining flanges at each extremity of the socket for locking the same against endwise movement in its seat.

4. A curtain rod socket circular throughout 70 its main body and polygonal at its lower extremity only, and integral retaining flanges at each extremity of the socket for preventing endwise movement thereof, one of said flanges being movable into retaining 75 position to secure the socket in place.

5. A sheet metal curtain rod socket provided at one extremity with an integral enlargement, and at the other extremity with a tab adapted to be deflected at an angle to the axis of the socket after the socket is installed, thereby cooperating with the enlargement to lock the socket against endwise movement.

In testimony whereof he hereunto affixes 85 his signature.

JOSEPH LEDWINKA.
